UNITED STATES PATENT OFFICE.

WILLIAM C. DAYHOFF, OF BRADLEY, ILLINOIS.

CONCRETE-MIXER.

No. 850,469.

Specification of Letters Patent.

Patented April 16, 1907.

Application filed May 14, 1906. Serial No. 316,673.

To all whom it may concern:

Be it known that I, WILLIAM C. DAYHOFF, a citizen of the United States, residing at Bradley, in the county of Kankakee, State of Illinois, have invented certain new and useful Improvements in Concrete - Mixers, of which the following is a specification, reference being had to the accompanying drawings.

10 This invention relates to improvements in concrete-mixers, and especially to that class of machines for mixing concrete that make use of a revoluble drum for the mixing-chamber. Its object is to provide a new and improved arrangement of the parts which not only insures these parts being held securely in working position, but also permits them to be readily disengaged from the rest of the machine for the purpose of moving it and as 20 easily reassembled for work.

Another object is to provide new and improved means for delivering the mixed concrete to a wheelbarrow or other receptacle without having to discontinue the operation 25 of the machine, thus increasing materially the amount of work able to be done by the machine. This construction also does away with the necessity for tipping the drum, which has been necessary in some constructions for emptying the drum of the mixed 30 material.

A further object is to improve generally the construction of concrete-mixers in sundry details hereinafter pointed out.

35 I accomplish these objects by means of the devices shown in the drawings and hereinafter specifically described.

That which I believe to be new will be pointed out in the claims.

40 In the drawings, Figure 1 is an end elevation of my improved machine. Fig. 2 is a section taken at line 2 2 of Fig. 3. Fig. 3 is a section taken at line 3 3 of Fig. 1. Fig. 4 is a detail, partly in section, showing one of the devices for elevating the mixed material. Fig. 5 is a detail, being an end view of the 45 part shown in Fig. 4. Fig. 6 is a detail showing one of the brackets and rollers on which the drum is mounted. Fig. 7 is a section 50 taken at line 7 7 of Fig. 6, showing also the upright to which the bracket is attached.

Referring to the drawings, 8 9 indicate side bars, and 10 cross-bars, of the base-frame of the machine, the cross-bars 10 being mortised in the side bars 8 9 or otherwise suit-

ably secured thereto. As best shown in Figs. 1 and 3, from each of these side bars 8 9 rise a pair of uprights, (indicated by 11 and 12, respectively,) which uprights, together with cross-bars 13, form standards for supporting the working parts of the machine. Each standard is reinforced by brace-rods 14 60 15, extending diagonally from the uprights 11 12 to the side bars 8 9, respectively, and firmly secured to these parts. 65

Each of the standards 11 12 has attached to its inside face along the cross-bar 13, by means of bolts, a heavy metal plate 16, from each end of which rises a bracket 16^a, integral with said plate, as shown in Fig. 7, to 70 receive a roller 18, which is revolvably mounted on a bolt 17, which passes through the upper end of the arm 16^a and one of the uprights 11 12.

19 indicates a drum, preferably of sheet 75 metal, consisting of the cylinder 20 and the end disks 21, which are riveted or otherwise suitably joined thereto. Each of these end disks 21 is provided with a large round central opening 22, at the edge of which there is 80 riveted or otherwise suitably secured an annular channel-iron 23. As shown in Figs. 6 and 7, the webs of these channel-irons are adapted to rest upon the rollers 18, thus making the drum 19 revolvable. 85

24 indicates a pair of bearing-blocks suitably attached to about the middle points of two of the cross-bars 10, which blocks form a bearing for the shaft 25, upon which is secured between the blocks 24 a sprocket-wheel 26. 90 On one end of the shaft 25 is secured a sprocket-wheel 27, through which said shaft 25 is driven from any suitable source of power. Upon the outside of the drum 19 is secured a sprocket 28 in alinement with the 95 sprocket 26, from which the drum is driven by means of the chain 29.

30 indicates a guard, of metal or other suitable material, running under the chain 29 from one to another of the cross-bars 10. 100

From the top of each upright 11 to the top of the upright 12, directly opposite it and resting upon these uprights, are two bars 31, having holes in their flattened ends which fit over pins 32 in the upper ends of the uprights 11 12. 105

Referring to Fig. 3, 33 34 indicate chutes, each comprising a bottom plate and two side plates, which in the construction shown are of sheet metal and are made integral. Near 110

the lower end of the chute 33 in the construction shown there are riveted to each of the outside faces of the side plates, diagonally across such faces, two angle-irons 35, the free sides of the angle-irons forming a housing adapted to engage the uprights 12 and maintain the chute at the proper angle. Near the upper end of the chute 33 in the construction shown there is riveted to the outside face of each of the side plates a hook 36, which hooks engage and rest upon the rods 31, holding the chute at the proper elevation. Near the upper end of the chute 34 are riveted on each side two angle-irons 37, which engage the uprights 11 and maintain the chute at its proper angle. 38 39 indicate two blocks suitably secured to the uprights 11 to hold the chute 34 at the proper elevation. It is thus seen that the rods 31 and chutes 33 and 34 can be very readily applied to the machine and disengaged therefrom, and yet are very securely held in position under working conditions.

40 indicates a rod extending between the two end disks and having its ends mounted in the same a short distance from the side of the cylinder. Although I have shown only two of such rods, it is understood that any appropriate number may be employed.

30 41 indicates a rod which extends through the drum and which has secured upon it a plate 42, which extends almost the full length of the drum, as shown in Fig. 4. On one end of the rod 41 is a head 43, between which and the end 21 of the drum 19 is interposed a coiled spring 44. The rod 41 is mounted in the ends 21 of the drum 19 and is easily turned or slid therein. Hence the spring 44 normally holds the head 43 of the rod away from the drum, holding the plate 42 in the position shown in Fig. 4, so far as the longitudinal movement of the plate is concerned.

45 indicates a lever on the end of the rod 41 for regulating the position of the rod and the plate attached thereto.

46 indicates a rod extending between the ends of the drum, against which rod the plate 42 is adapted to rest when in the position shown in dotted lines in Fig. 2.

50 When the plate 42 is in the position shown in solid lines in Fig. 2, the lever 45 is in the position shown in solid lines in Fig. 5, where it is held by the stop 47. If it is desired to change the position of the plate 42, the lever 45 is pulled out to a point beyond the stop 47 against the action of the spring 44, and the lever is turned to the position shown in dotted lines in Fig. 5, when the plate will have assumed the position shown in dotted lines in Fig. 2, upon 60 which the action of the spring returns the plate to its normal position, carrying the lever 45 again to a position where the stop 47 prevents displacement. I have described only one of these plate devices, the other one 65 shown being a duplicate of the one described.

I do not limit myself to the use of two of these plate devices, as any appropriate number of them may be employed.

The operation of the machine is as follows: The plate 42 being in the position shown in solid lines in Fig. 2, power is applied to the sprocket 25, driving the drum in the direction indicated by the arrow in Fig. 2. The materials to be mixed are then fed into the drum through the chute 34. After two or three revolutions of the drum, or even after one, the materials will be found to be thoroughly mixed, the rods 40 and plates 42 holding momentarily parts of the materials, and thus facilitating the mixing. While the drum is still being rotated the plates 42 are turned to the position shown in dotted lines in Fig. 2 in the manner hereinbefore described, and a portion of the materials in the drum is raised by each plate 42 as these plates successively rise, as will be readily understood. The material so raised slips off these plates into the chute 33, from where it is delivered onto the ground or into wheelbarrows or other receptacles, as desired. As a usual thing two or three revolutions are sufficient almost completely to empty the drum, although this would depend, of course, upon the amount of materials being mixed and upon the size and number of the plates 42.

It is seen that no time is lost in intermittently stopping and starting the machine and no lifting or tilting of the drum loaded with mixed materials is necessary.

Although I have described my invention as being in connection with a concrete mixer, it will be understood that the machine provided with my improvements might be used for mixing other materials, and I do not desire to limit my invention strictly to concrete-mixers.

What I claim as my invention, and desire to secure by Letters Patent, is—

1. In a concrete-mixer, the combination with a revoluble drum having an opening in one end, and two uprights adjacent to said opening, of a chute leading into said drum and having a diagonal housing across each side slidably engaging one of said uprights, and a block on each of said uprights for supporting said chute.

2. In a concrete-mixer, the combination of a drum mounted revolvably between two standards and having an opening in each end, a chute leading from said drum, said chute having a diagonal housing on each side slidably engaging one of said standards, parallel rods extending through said drum and connecting said standards, and a hook on each side of said chute near its upper end engaging said rods.

3. In a concrete-mixer, the combination of a revoluble drum, a plate pivoted at its edge near the inner surface of the drum and

adapted to be swung into and out of position to elevate the materials in the drum as it is rotated, means outside the drum for turning the plate into and out of elevating position and locking it in place, and a rod 46 carried by the drum for supporting the plate in elevating position.

4. In a concrete-mixer, the combination with a revoluble drum and a chute leading therefrom, of a rod slidably pivoted near the inner surface of the drum and extending through one end of the same, a lever on the outer end of the rod, a stop on the end of the drum for locking said lever in position, said rod being movable longitudinally to free said lever from contact with said stop, and a plate secured to said rod inside said drum.

5. In a concrete-mixer, the combination with a revoluble drum and a chute leading therefrom, of a rod slidably pivoted near the inner surface of the drum and extending through both ends of the drum, a head on one end of said rod, a spring interposed between said head and said end of the drum, a lever on the other end of said rod, a stop on the end of the drum for locking said lever in position, said rod being movable longitudinally to free said lever from contact with said stop, and a plate secured to said rod inside said drum.
